CLAIM

The ornamental design for a boot dryer as shown and described.

DESCRIPTION

FIG. 1 is a top front perspective view of a boot dryer;

FIG. 2 is a top rear perspective view thereof;

FIG. 3 is a bottom perspective view thereof;

FIG. 4 is a top view thereof;

FIG. 5 is a bottom view thereof;

FIG. 6 is a right side view thereof;

FIG. 7 is a left side view thereof;

FIG. 8 is a front view thereof; and,

FIG. 9 is a rear view thereof.

The broken lines shown in the figures are for the purpose of illustrating portions of the boot dryer and form no part of the claimed design.
